UNITED STATES PATENT OFFICE.

JAMES H. CARITHERS, OF DANVILLE, ILLINOIS.

CARBURETER.

1,179,278.

Specification of Letters Patent. Patented Apr. 11, 1916.

Application filed April 9, 1915. Serial No. 20,277.

To all whom it may concern:

Be it known that I, JAMES H. CARITHERS, a citizen of the United States, residing at Danville, in the county of Vermilion and State of Illinois, have invented new and useful Improvements in Carbureters, of which the following is a specification.

This invention relates to carbureters, the broad object in view being to produce a carbureter which, without any change or alteration therein after leaving the factory, may be utilized for vaporizing liquid fuels or fuel oils of relatively higher and lower specific gravity and volatility, the change from one fuel oil to the other being effected instantly by merely shifting a single valve.

In the use of fuel oils of low specific gravity, it has been found necessary to run a motor or engine until it is heated sufficiently to volatilize a heavier grade of oil in order that said oil may be thoroughly vaporized before reaching the engine. The carbureter of this invention is designed to primarily start the engine with oil of a comparatively high test and after the engine becomes sufficiently heated, to operate said engine with a fuel oil of lower specific gravity.

With the above and other objects in view, the invention consists in the novel construction, combination and arrangement of parts, as herein described, illustrated and claimed.

In the accompanying drawings:—Figure 1 is a top plan view of the carbureter, including the means for conducting the air thereto and heating the air which is used in connection with one of the carbureting chambers. Fig. 2 is a side elevation of the same. Fig. 3 is a vertical longitudinal section through the carbureter. Fig. 4 is a vertical cross section through the same. Fig. 5 is a fragmentary section showing the means for varying the area of the notch or opening in the throttle valve when the latter is closed. Fig. 6 is an end elevation of the air heating device, showing the exhaust pipe of an engine in cross section.

The main body of the carbureter comprises an upper chamber-like section 1, a bottom section 2, and an intermediate nozzle plate 3 which divides the upper and lower sections from each other and also divides the interior of the carbureter into a bottom fuel section and a superimposed carbureting section.

Within the bottom section is a vertical

partition wall 4 which divides the bottom section into a gasoline chamber or reservoir 5 and a kerosene chamber or reservoir 6. A like central vertical partition wall 7 divides the upper section of the carbureter into a gasoline carbureting chamber 8 and a kerosene carbureting chamber 9. At this point it may be stated that the term gasoline herein used implies a liquid fuel of a relatively high specific gravity and volatility, while the term kerosene is used to imply a liquid fuel of relatively lower specific gravity and volatility, the terms referred to being used simply for the sake of convenience in describing the carbureter.

The nozzle plate 3 which is shown in plan view in Fig. 6 comprises a pair of upstanding float receiving pockets 10 in each of which is arranged a float 11 as best illustrated in Fig. 4, said float being adapted to rise and fall in accordance with the level of liquid therein. Each float 11 is preferably of hollow metal construction and provided with a tube 12 extending vertically therethrough and internally threaded to be engaged by the threads 13 of a vertically extending stem 14 provided at its upper end with an operating cap or head 15. The stem 14 extends entirely through the float 11 and has a ball and socket or swivel joint at 16 with a lever 17 pivotally mounted at 18 within the fuel chamber and connected at 19 to a needle valve 20 forming one of the fuel inlet valves, it being understood that there is a fuel inlet valve for each grade of fuel used.

21 designates nipples to which the fuel feed pipes lead.

It will now be seen that by revolving the stem 14 by means of the milled head 15, the float 11 may be raised and lowered according to the amount of fuel necessary to be maintained in the fuel chamber. The construction referred to is duplicated in each of the fuel chambers. The stems 12 extend through openings 22 in the top section 1 to the carbureter where they are easily accessible for effecting the adjustment referred to.

The nozzle plate is also provided with a plurality of depressions or basins 23 and by reference to Fig. 4 it will be observed that two of such depressions or basins are formed at each side of the partition 4. In each of said depressions there is arranged a nozzle 24 so that there are two nozzles

in communication with each fuel chamber and arranged to discharge into the superimposed carbureting chamber. By preference, the nozzles on the kerosene side of the carbureter are provided with heating flanges 25 to assist in vaporizing the kerosene. The flanges 25 absorb some of the heat from the incoming current of the hot air from the jacket 39 and raise the temperature of the fuel passing through the nozzles 34. Drain tubes 26 lead from each of the depressions 23 through the bottom section of the carbureter 6 so as to provide for carrying off excess fuel oil in case either carbureting chamber becomes flooded. Each of the fuel chambers is also provided with a drain cock 27.

In order to assemble the members 1, 2 and 3 of the carbureter, each of said members is flanged where they meet and are secured together by fasteners 28 which may consist either of bolts or screws.

Air is admitted to the carbureter by means of pipes or conduits 29 and 30, the pipe 29 furnishing air for the kerosene side of the carbureter and the pipe 30 furnishing air for the gasoline side thereof. At their ends adjacent to the carbureter body, said pipes are flanged as shown at 31 and 32 which is also flanged as shown at 33 and secured by fasteners 34 to the carbureter body. The coupling 32 is preferably rectangular in cross section and the adjacent abutting ends of the pipes 29 and 30 are therefore correspondingly squared. For the remainder of their length the pipes 29 and 30 are preferably round in cross section. The pipe 29 which furnishes air for the kerosene side of the carbureter is connected at one end to the discharge nozzle 35 of an air heating device associated with the exhaust pipe 36 of an engine. This part of the apparatus comprises one or more bands 37 of heat retaining material which extends around the exhaust pipe as shown in Fig. 6 and forms a heat absorbing strap, the same being split so that it may be placed around the exhaust pipe and being held in place by means of a clamping screw 38. A sheet metal casing or jacket 39 is fastened along its marginal edges at 40 to the heat absorbing strap 37, said casing being substantially of inverted U-shape and having one or more openings in the top thereof controlled by manually controlled cold air admission dampers 41 which may be opened to any desired extent to regulate the amount of cold air to be admitted into the casing 29 in accordance with the atmospheric temperature, it being necessary sometimes in summer weather to admit air at the point or points referred to in order to avoid overheating the engine. Attached to each of the heat absorbing straps 37 is a substantially

U-shaped heat conducting strip 42, the same being fastened at 43 to the strap 37. The strip 42 may be of any desired shape so as to conduct its heat to the air drawn into the casing 39. Thus the air supply to the kerosene side of the carbureter is heated by the intake pipe before reaching the carbureter body.

The coupling 32 contains a plurality of air inlet valves 44, one for each of the 75 pipes 29 and 30, the coupling 32 being centrally divided by a partition 45 into two compartments communicating respectively with the two carbureting chambers of the carbureter. Each of the valves 44 is pivotally mounted at 46 within its respective compartment, the pivot 46 being located above the center of the valve and extending horizontally, whereby the valve 44 is rendered self-closing by gravity but is adapted to be opened by air pressure to the dotted line position shown in Fig. 1. Thus each valve 44 is opened and closed automatically in accordance with which side of the carbureter is being used. 90

At the discharge end of the carbureter there is arranged an outlet neck 47 flanged as shown at 48 to enable the same to be bolted, screwed or otherwise fastened to the intake pipe or manifold of an internal combustion engine. Within the neck 47 is mounted a butterfly throttle valve 49 the stem 50 of which is provided with an operating lever 51 and also provided with a stop 52 adapted to limit the closing movement of said throttle valve. The body of the valve 49 is formed with a notch 53 preferably V-shaped so that when the valve 49 is in its closed position there will be an opening of sufficient area to admit carbureted air to the engine sufficiently to keep the same running at a low rate of speed. The size or area of the notch 53 is variable by means of an adjustable plug 54 tapered as shown to conform to the shape of the notch 53, said plug 54 being threaded through an opening 55 in the neck 47 and provided with means for turning said plug, said means shown as consisting of a screw driver neck 55' and a lock nut 56, all as shown in Fig. 5.

shown in Fig. 5.

Between the throttle valve 49 and the interior of the main body of the carbureter there are two oppositely located quadrant shaped ports 57 adjacent to which there is 120 pivotally mounted on a vertical axis, an angle valve 58 consisting of two wings arranged substantially at right angles to each other as shown in Fig. 3. The valve 58 is mounted fast on a vertical stem 59 extending 125 through the top of the upper section of the carbureter where it is provided with an operating handle 60. By turning the valve in one direction, the flow of the mixture through one of the ports 57 is cut off and ad- 130

nitted through the other port, and vice versa when the valve is moved through an arc of ninety degrees in the opposite direction. In the preferred embodiment of the invention the neck 47 is formed separately from the body of the carbureter and flanged and fastened thereto as shown at 61.

From the foregoing description, taken in connection with the accompanying drawings, the operation of the carbureter will now be clear. The carbureter is divided into two sides, so to speak, one side being designed to receive gasoline or other highly volatile fuel oil, while the other side is adapted to receive fuel oil of a lower grade such as kerosene. The air conducted by the kerosene side of the carbureter is first heated by the exhaust pipe of the engine while the air admitted to the gasoline side of the carbureter does not usually require to be heated. In cold weather or at other times when the engine is cold, the angle valve 58 is moved to a position which will allow air to be taken through the port 51 on the gasoline side of the carbureter. The engine is then started and is operated with gasoline for a sufficient length of time to insure the engine and the adjacent parts of the engine thoroughly heated. As soon as the pump is started, the angle valve 58 is quickly moved by means of the lever or handle thereto and held in its movement to the other, thereby cutting off the gasoline side of the carbureter and opening up the kerosene side. The engine thereafter is operated by the kerosene which by reason of the heating arrangement hereinabove described is thoroughly vaporized and rendered into an explosive mixture before it reaches the combustion chamber or chambers of the engine. It will thus be seen that no change or alteration whatever is necessary in the carburetor after it leaves the factory. The motor may be started with gasoline and the operation thereof continued with kerosene.

By reference to Figs. 5 and 6 it will be noted that the nozzles 21 of the kerosene carbureter are arranged in different longitudinal and transverse planes; that is to say one of the nozzles, for example, is arranged nearer to the discharge end of the carbureter than the other, thereby providing for an equal flow of fuel whether the machine is ascending or descending a steep grade. Furthermore, by having the two nozzles of

each mixing chamber on opposite sides thereof, one or the other of said nozzles will always be effective whether the machine is on a steep hill inclining to the right or to the left. On the gasoline side of the carbureter 60 it is not necessary to arrange the nozzles 24 one in advance of the other but this arrangement is resorted to in the kerosene side for the reason that this is the side of the carbureter which is used for the greater part of 65 the time when the machine is in actual use and necessarily ascending and descending grades, the gasoline side of the carbureter being ordinarily used only while the machine is standing still on level ground. 70

What I claim is:—

1. In a carbureter, independent fuel chambers for relatively light and heavy fuel oils, means associated with each of said chambers for maintaining the fuel oil at a predetermined level therein, a corresponding number of independent carbureting chambers superimposed above said fuel chambers, a nozzle plate interposed between the fuel and carbureting chambers and provided with nozzles, 80 said nozzle plate being also formed to provide pockets for elements of the level maintaining means, means for conducting air to said carbureting chambers, a mixture outlet neck having a port for each carbureting chamber, and means for closing one of said ports and opening the other port.

2. In a carbureter, independent fuel chambers for relatively light and heavy fuel oils, means associated with each of said chambers for maintaining the fuel oil at a predetermined level therein, a corresponding number of independent carbureting chambers superimposed above said fuel chambers, a nozzle plate interposed between the fuel and carbureting chambers and provided with nozzles, 90 located in different longitudinal and transverse planes with respect to the engine, means for conducting air to said carbureting chambers, a mixture outlet neck having a 100 port for each carbureting chamber, and means for closing one of said ports and opening the other port.

In testimony whereof I affix my signature in presence of two witnesses.

JAMES H. CARITHERS.
